US0D1080587S

(12) **United States Design Patent** (10) **Patent No.:** **US D1,080,587 S**
(45) **Date of Patent:** **** Jun. 24, 2025**

(54) **EARPHONE**

(71) **Applicant:** **Shenzhen Lianqiao Network Technology Co., Ltd**, Shenzhen (CN)

(72) **Inventor:** **Sican Dong**, Chaozhou (CN)

(73) **Assignee:** **Shenzhen Lianqiao Network Technology Co., Ltd**, Shenzhen (CN)

(**) **Term:** **15 Years**

(21) **Appl. No.:** **29/972,387**

(22) **Filed:** **Nov. 10, 2024**

(51) **LOC (15) Cl.** **14-01**

(52) **U.S. Cl.**

(57) **CLAIM**

The ornamental design for an earphone, as shown and described.

DESCRIPTION

FIG. 1 is a front perspective view of a right-side earphone, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of a left-side earphone showing my new design;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof; and,

FIG. 17 is a front view of the right-side and left-side earphone.

The broken lines in the drawings illustrate the portions of the earphone, which form no part of the claimed design.
